UNITED STATES PATENT OFFICE.

JOHN BATH AND ERNEST A. WALKER, OF WORCESTER, MASSACHUSETTS, ASSIGNEES,
BY MESNE ASSIGNMENTS, TO SAID BATH.

RELIEVING MECHANISM FOR GRINDING MACHINES.

Application filed October 7, 1924. Serial No. 742,227.

This invention relates particularly to a machine for grinding grooves in taps and hobs or other similar articles, in which machine provision is made for simultaneously relieving the threads or grooves as they are being ground. It is the object of our present invention to provide improved mechanism by which the depth of cut may be accurately determined without interfering with the regular operation of the relieving devices.

Another object of our invention is to provide for increased accuracy in the axial feed of the grinding wheel. Our invention further relates to arrangements and combinations of parts which will be hereinafter described and more particularly pointed out in the appended claims. A preferred form of our invention is shown in the drawings in which

Fig. 1 is partial front elevation of a grinding machine embodying our improvements.

Fig. 2 is an end elevation of the parts shown in Fig. 1.

Fig. 3 is a detail plan view of certain parts, looking in the direction of arrow 3 in Fig. 2.

Fig. 4 is a sectional end elevation, taken along the lines 4-4 in Fig. 1.

Fig. 5 is a detail front elevation, looking in the direction of the arrow 5 in Fig. 4.

Fig. 6 is a detail plan view, looking in the direction of the arrow 6 in Fig. 5.

Fig. 7 is a partial side view of a hob, and

Fig. 8 is a diagrammatic view indicating the operation of the relieving cams.

Referring to the drawings we have shown parts of a grinding machine comprising a bed or frame 10 on which a hob or other work H is rotatably mounted between centers 11 and 12. The center 11 is held in the driving spindle 13 of the machine and the center 12 is mounted in the tail stock 14, slidable on an extension of the head 30.

A grinding wheel W (Figs. 1 and 3) is mounted on a wheel spindle 15 carried by an axially movable wheel carriage 16. The carriage 16 is provided with a nut or boss 16' which engages a lead screw 17 (Fig. 3) rotatably mounted in the bed or frame 10 and having a gear 18 (Figs. 2 and 3) fast thereon. The gear 18 is connected through an intermediate pinion 19 and gear 20 to a second pinion 21 mounted on a stud 22 and having a hand lever or arm 23 fast with said pinion.

The arm 23 is provided with a handle 24

and also with a spring pressed plunger 25. 55 A stop 26 is positioned for engagement by plunger 25. The gears 19, 20 and 21 are adjustably mounted in a plate 27 secured to the frame 10 by bolts 28 (Fig. 2) which permit angular adjustment of the plate. The spring 60 plunger 25 is also longitudinally adjustable in a slot 29 in the arm or lever 23.

In the preferred operation of our machine the change gears 18, 19, 20 and 21 are so selected that one revolution of the arm 23 65 and pinion 21 will move the wheel carriage 16 axially by the space between adjacent threads or grooves to be cut. In using the feeding device, the operator simply pulls the plunger 25 to clear the stop 26 and then 70 releases the plunger and rotates the arm 23 until the plunger again engages the stop.

The driving spindle 13 is rotatably mounted in a head 30 which is pivoted upon a bearing sleeve 31 (Fig. 4) mounted on the frame 75 10. The spindle is rotated through change gearing from a driving pulley 32 and belt 33, or in any other convenient manner.

A cam shaft 34 is rotatable in bearings 35 projecting forward from the spindle head 30. 80 This cam shaft 34 is driven through change gears 35, 36, 37 and 38 (Fig. 2) from the driving spindle 13. By a suitable selection of change gears, the cam shaft 34 may be rotated in any desired speed relation to the 85 spindle 13 and the work H.

A series of relieving cams 40 (Figs. 1 and 5) are mounted on the shaft 34 in position for engagement by a cam roll 41 mounted on a bearing block 42 which is slidably secured 90 to a swinging plate 43, pivoted at 44 to a bracket 45, which in turn is secured to the frame 10. The swinging plate 43 has a wearing plate 46 secured to the under side thereof and engaged by cams or eccentrics 50 (Fig. 95 5) mounted on a second cam shaft 51. The bearing bracket 42 is preferably recessed as indicated in Fig. 5 to receive oil or other lubricant.

The cam shaft 51 is provided with a handle 52 by which it may be moved angularly to raise and lower the roll 41. A latch 53 on the handle 52 cooperates with a toothed segment 54 mounted on the end of the machine frame 10 and may be disconnected manually 105 therefrom. A limit stop 55 for the handle 52 is slidable on the segment 54 and may be secured in any desired position thereon.

Having described the construction of our improved relieving mechanism, the operation thereof is as follows:

Assuming that a hob H (Fig. 7) is to be provided with a series of parallel grooves 60, it will be evident that the grinding wheel must be separated from the work while the wheel is moved axially from one groove to the next. For this purpose, the handle 52 is 10 swung to the position shown in Fig. 2, in which the plate 43 rests upon the smallest parts of the cams or eccentrics 50. This allows the spindle head 30 to swing forward so that the hob H clears the edge of the wheel W which is then moved axially by use of the feed arm 23.

The handle 52 is then swung to the left, as indicated by the arrow *a* in Fig. 2 and is held in any desired position by engagement of the 20 latch 53 with the segment 54.

An index line 61 may be provided on a disc 62 on the spindle 13 and an index finger 63 cooperates with the index line 61. The operator, by watching the position of the line 25 61, can easily determine when each revolution of the hob is completed, and can then advance the handle 52 one or more notches along the segment 54, until the handle finally engages the adjusted stop 55 which corresponds to the depth of cut.

In every position of the handle 52 the relieving cams 40 are operative to alternatively move the work toward and from the wheel W, thus relieving the back portion of each 30 tooth of the hob.

By our improved construction, the relieving cams operate continually and the setting thereof is not disturbed when the work is withdrawn from the wheel. Both the axial and transverse relation of the wheel and work may be very accurately determined. The work is easily withdrawn from contact 40 with the wheel and is as easily restored to a predetermined position.

Having thus described our invention and the advantages thereof, we do not wish to be limited to the details herein disclosed, otherwise than as set forth in the claims; but what we claim is:—

50 1. In a grinding machine, a wheel spindle, a work rotating member, means to rotate said spindle and member, means to regularly vary the relative positions of said spindle and member, and means including an auxiliary cam plate arranged to co-act with said first means to change the locus of such variations.

60 2. In a grinding machine, a wheel spindle, a work rotating member, means to rotate said spindle and member, means to regularly vary the relative positions of said spindle and member, said means comprising a device to produce repeated relieving movements of one of said rotating parts transversely to the axis thereof, and means including an aux-

iliary cam plate arranged to co-act with said first means to change the locus of said relieving movements.

3. In a grinding machine, a wheel spindle, a work rotating member, a head in which one of said parts is rotatably mounted, means to rotate said spindle and member, a relieving device effective to produce oscillating movements of said head to vary the relative positions of said rotating parts, an auxiliary cam plate engaging said relieving device, and means to move said plate to produce an additional angular movement of said head. 70

4. In a grinding machine, a wheel spindle, a work rotating member, means to rotate said spindle and member, a head in which one of said rotating parts is mounted, means to vary the relative positions of said rotating parts, said means including a relieving device effective to produce oscillating movements of said head, an auxiliary cam plate engaged by said device, and additional means to move said plate and device to give said head and one rotating part an additional independent movement relative to the other rotating part. 80 85

5. In a grinding machine, a wheel spindle, a work rotating member, means to rotate said spindle and member, a head in which one of said rotating parts is mounted, means to vary the relative positions of said rotating parts, 90 said means including a relieving cam effective to produce oscillating movements of said head, an auxiliary plate co-operating with said cam and having a stationary operative position, and means to shift said operative 100 position to vary the angular position of said head.

6. In a grinding machine, a wheel spindle, a work rotating member, means to rotate said spindle and member, a head in which one of said rotating parts is mounted, means to vary the relative positions of said rotating parts, said means including a relieving cam effective to produce oscillating movements of said head, a roll engaged by said cam, and additional means including an auxiliary cam plate 110 arranged to move said roll and cam to give said head an additional independent movement relative to the other rotating part. 110

7. In a grinding machine, a wheel spindle, a work rotating member, means to rotate said spindle and member, a head in which one of said rotating parts is mounted, means to vary the relative positions of said rotating parts, said means including a relieving cam effective to produce oscillating movements of said head, a cam-engaging roll, a swinging plate on which said roll is mounted, and manual means to move said plate angularly. 115 120

8. In a grinding machine, a wheel spindle, a work rotating member, means to rotate said spindle and member, a head in which one of said rotating parts is mounted, means to vary the relative positions of said rotating parts, said means including a series of relieving 125 130

cams each effective to produce oscillating movements of said head, an element co-operating with a selected cam and having a stationary operative position, and means to shift said operative position both axially and vertically relative to said head.

9. In a grinding machine, a wheel spindle, a work rotating member, means to rotate said spindle and member, a head in which one of said rotating parts is mounted, means to vary the relative positions of said rotating parts, said means including a relieving cam effective to produce oscillating movements of said head, a cam-engaging roll, a swinging plate on which said roll is mounted, and manual means to move said plate angularly, said manual means comprising a cam supporting said plate, and means to move said cam angularly.

10. In a grinding machine, a wheel spindle, a work rotating member, means to rotate said spindle and member, a head in which one of said rotating parts is mounted, means to vary

the relative positions of said rotating parts, said means including a relieving cam effective to produce oscillating movements of said head, a cam-engaging roll, a swinging plate on which said roll is mounted, and manual means to move said plate angularly, said manual means comprising a cam supporting said plate and devices to accurately determine the angular movement of said cam.

11. In a grinding machine, in combination, a grinding wheel, a work rotating member, means to produce alternating relieving movements between said wheel and work rotating member, additional means to change the locus of such movements, and means to produce relative axial movement of said wheel and work rotating member to an accurately predetermined extent.

In testimony whereof we have hereunto affixed our signatures.

JOHN BATH.
ERNEST A. WALKER.
